UNITED STATES PATENT OFFICE

FRANK B. PUTT, OF MEADOWBROOK, PENNSYLVANIA, ASSIGNOR TO BRANDLE & SMITH COMPANY, OF PHILADELPHIA, PENNSYLVANIA, A CORPORATION OF PENNSYLVANIA

DESIGN FOR A BOTTLE OR SIMILAR CONTAINER

Application filed March 12, 1931. Serial No. 39,049. Term of patent 14 years.

To all whom it may concern:

Be it known that I, FRANK B. PUTT, a citizen of the United States, residing at Meadowbrook, in the county of Montgomery, State of Pennsylvania, have invented a new, original, and ornamental Design for Bottles or Similar Containers, of which the following is a specification, reference being had to the accompanying drawings, forming part thereof.

I claim:

The ornamental design for a bottle or similar container, as shown.

FRANK B. PUTT.
